UNITED STATES PATENT OFFICE.

ARTHUR B. CURRY, OF HIGHLAND PARK, MICHIGAN, ASSIGNOR OF FIFTY-ONE ONE-HUNDREDTHS TO MICHAEL A. MAHONEY, OF DETROIT, MICHIGAN.

SPARK-PLUG.

1,315,214.

Specification of Letters Patent. Patented Sept. 9, 1919.

Application filed January 31, 1919. Serial No. 274,188.

To all whom it may concern:

Be it known that I, ARTHUR B. CURRY, a citizen of the United States, residing at Highland Park, county of Wayne, State of Michigan, have invented a certain new and useful Improvement in Spark-Plugs, and declare the following to be a full, clear, and exact description of the same, such as will enable others skilled in the art to which it 10 pertains to make and use the same, reference being had to the accompanying drawings, which form a part of this specification.

This invention relates to spark plugs, and its object is to provide a spark plug with electrodes arranged in such manner that oil splashed or accumulating thereon in operation of the engine drains away from the 15 sparking point. By this arrangement the electrodes at the point of discharge are 20 maintained comparatively free from oil whereby a maximum electrical discharge may take place. This general object and the various novel features of the invention are hereinafter more fully described and 25 claimed and shown in the accompanying drawings illustrative of the preferred form of the invention in which—

Figure 1 is an elevation of a spark plug embodying my invention.

Fig. 2 is an alternative form thereof.

The spark plug may be of any approved type in which is centrally mounted an electrode 1 carried in the usual insulating member 2 and provided with a terminal 3 for 35 connection with the electric wires. The character of the insulating body 2 is not material to this invention except that it be efficient for the purpose and may be secured in any approved manner in the body 4 of the plug as for instance by means of the 40 nut 5. The body 4 terminates in the usual threaded portion 6 by means of which it is secured in the head of an internal combustion engine and to the lower edge of and 45 electrically connected with this portion 6 (which is hollow in form) is an electrode 7 extending downwardly therefrom and bent back upon itself terminating at the point 8 adjacent the body of the electrode 1. It is 50 to be noted that this portion 8 from the bend to the end thereof lies at an angle to the electrode 1 so that, from the sparking point or end of the electrode, the said 55 reversely bent portion may gradually increase in distance from the part 1 to such

extent that toward the lower end thereof it is such a distance from the electrode 1 that no discharge may take place at that point. It is also to be noted that the electrode 1 extends considerably below the 60 sparking point and preferably below the bend in the electrode 7.

By this arrangement oil, which is splashed onto the electrodes during operation of the engine or that may accumulate thereon for 65 any commonly known cause, feeds down the electrodes by gravity away from the point of electrical discharge between the electrodes. This leaves the point 8 and the 70 part of the electrode 1 opposite thereto comparatively free from oil at all times, the tendency being for it to drain away from the said point of electrical discharge as before stated. By this arrangement 75 therefore, the electrodes are maintained comparatively free from oil at the point of electrical discharge and there is no material insulation of the electrodes one from the other. Further, the accumulation of carbon on the electrodes at the point of electrical 80 discharge is reduced to a minimum and thus the spark plug need be less frequently cleaned and at all times is capable of producing the maximum spark and consequently a more ready ignition of the fuel 85 in the cylinder.

It is evident that this result may be secured in other ways than the preferred way which is here shown in Fig. 1 but the essential characteristic of my form is to provide 90 the electrodes of such character and form that the oil accumulating thereon may drain away from the point of electric discharge. An alternative form is suggested in Fig. 2 in which the electrode 7^a is made flat particularly at the bend as shown providing 95 a comparatively large surface and aiding in drawing the oil away from the point of electric discharge 8^a, gravity being assisted by the capillary attraction more rapidly clearing the sparking points of oil. In this latter case it is also to be noted from the point 8^a to the bend of the electrode 7^a 100 the angle thereof is of the same character as the type of electrode 7 shown in Fig. 1. 105

I am aware of other spark plugs for internal combustion engines having an electrode provided with a rebent portion, but in all instances within my knowledge this rebent portion does not extend at such an 110

angle that the lower part thereof is sufficiently distant from the central electrode as to prevent sparking at that point. To accomplish the purpose of this invention it is essential that this angle be substantially as indicated in the drawing so that the point of electrical discharge is above the lowermost point of both electrodes and in such position that the oil may drain away from the point of electrical discharge.

Having thus briefly described my invention, what I claim is—

1. A spark plug for internal combustion engines comprising a body, a straight electrode extending centrally therethrough and insulated from the body, a second electrode in the electrical contact with the body and extending there below and having a reversely bent terminal portion extending from the point of the bend upward toward the central electrode and providing a spark gap of gradually increasing width downwardly from the point of nearest approach, said bent portion being thin or flat in form presenting a comparatively large depending surface onto which oil may flow away from the terminal point.
2. In a spark plug for internal combustion engines, a body, a straight central electrode extending through the body and insulated therefrom, a second electrode in electrical contact with the body and extending therebelow in the form of a V, the free end of which extends toward the central electrode, and providing a spark gap between the electrodes of a gradually increasing width, the said central electrode extending below the bend of said second electrode.

3. In a spark plug for internal combustion engines provided with a body, an electrode extending centrally therethrough and insulated from the body, a second electrode in electrical contact with the body and extending therebelow in the form of a V, the lower portion of which is thin or flat in form presenting a comparatively large surface and the terminal portion thereof being substantially circular in cross section and positioned adjacent the central electrode, the said central electrode extending below the lowest point of the second electrode substantially as and for the purpose described.

In testimony whereof, I sign this specification.

ARTHUR B. CURRY.
